(57) **CLAIM**

I claim the ornamental design for a rail road platform safety apparatus, as shown and described.

DESCRIPTION

FIG. 1 is a perspective view of a rail road platform safety apparatus, showing my new design with a grate thereof in an extended position;

FIG. 2 is a top plan view thereof;

FIG. 3 is a bottom plan view thereof;

FIG. 4 is a left-side elevational view thereof, the right-side elevational view being a mirror image thereof;

FIG. 5 is a front elevational view thereof;

FIG. 6 is a rear elevational view thereof;

FIG. 7 is a perspective view thereof, illustrated with the grate in a retracted position; and,

FIG. 8 is a left-side elevational view of FIG. 7, the right-side elevational view being a mirror image thereof.

The broken lines showing a railway platform and a train in FIG. 1 depict environmental matter and form no part of the claimed design.
